UNITED STATES PATENT OFFICE.

SIGFRIED TAUSSIG, OF PRAGUE, BOHEMIA, AUSTRIA-HUNGARY.

ELECTRIC FIRE AND BURGLAR ALARM.

SPECIFICATION forming part of Letters Patent No. 359,823, dated March 22, 1887.

Application filed June 24, 1886. Serial No. 206,097. (No model.) Patented in France May 15, 1886, No. 176,177; in Belgium May 15, 1886, No. 73,128; in Italy June 30, 1886, XX, 19,936, XXXIX, 296; in Luxembourg August 15, 1886, No. 723; and in Spain November 2, 1886, No. 6,206.

To all whom it may concern:

Be it known that I, SIGFRIED TAUSSIG, attorney at law, a subject of the Emperor of Austria, residing at Prague, in the Province of Bohemia, in the Empire of Austria-Hungary, have invented certain new and useful Improvements in Electric Fire and Burglar Alarms, (for which Letters Patent have been obtained in France, No. 176,177, dated May 15, 1886; in Belgium, No. 73,128, dated May 15, 1886; in Italy, XX, 19,936, and XXXIX, 296, dated June 30, 1886; in Luxembourg, No. 723, dated August 15, 1886, and in Spain, No. 6,206, dated November 2, 1886;) and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Referring to the drawings, Figure 1 is a diagram of my improved system of fire and burglar alarm. Fig. 2 is an elevation of the circuit-breaker or electric-impulse transmitter for the local stations and the parts connected therewith and controlling the same.

This invention relates to that class of devices known as "fire or burglar alarms" which are operated and controlled by electric currents.

The object of my invention is to provide improved means whereby an alarm, either audible or visible, or a permanent or recorded alarm, may be given at a central station distant therefrom in case of a fire breaking out, or in case of an attempted burglary at such distant station.

To these ends the invention consists in an alarm system comprising a main or central station, an indicator at said station, a main electric circuit, any number of secondary stations, a local circuit, and a transmitting-instrument for each secondary station, the latter operating to transmit electric impulses differing in nature from those transmitted by the instruments of the other local stations to said central or main station, substantially as hereinafter fully described.

The invention further consists in the com-

bination, with each local circuit, of the system of a shunt-circuit and a signaling device in said circuit, substantially as hereinafter fully described.

Lastly, the invention consists in some of the details of construction of the instruments or apparatus used, substantially as hereinafter fully described.

In the drawings, A indicates the main circuit, that extends from a main or central station, I, to any desired number of local stations, 1 2 3, &c., connected with the main line by branch lines or wires b'. Each of the local stations, which may be a public building, bank, warehouse, or other building, has a local circuit, H, in which are included all the points, h, to be protected—such as shutters, doors, windows, safes, &c. In order to close the local circuit when any one of the points h is unauthoritatively tampered with without necessarily closing it at all points h, these are connected in multiple arc in any desired or well-known manner. In the main and each local circuit is interposed a transmitter, which consists, essentially, of a circuit-breaker operated from a suitable train of clock-gearing, C.

The circuit-breaker, its operating mechanism, and parts operating in conjunction therewith are mounted on a suitable frame, and said circuit-breaker consists of a metallic wheel, B, that has upon its periphery a predetermined number of insulated points or strips, bx, arranged in a predetermined manner and of a predetermined extent, so that the contacts of all the wheels of the transmitters will differ from one another and a different signal will be transmitted from each local station to the main or central station, the line-current passing from the central station battery Y through the transmitter of each station, through its frame, and thence by wire b' to earth, as at G.

When the transmitter is at rest, and whether the system is used with a normally-interrupted or a normally-closed circuit, one of the strips or points bx will lie in contact with a spring, b, that is connected with the branch wire b' of the main line A.

D is a lever fulcrumed at d, one end, d², of

which lever is hooked and engages a notch in an annular projection of the wheel B, the other end, d^3 , of said lever lying in the path of the outer end, e^2 , of an armature-lever, E', fulcrumed at e , the said parts forming an escape-
5 ment; and E is an electro-magnet included in the local circuit H. The wheel B is connected with the transmitting-wheel c of the train of clock mechanism C by means of a toothed
10 wheel, b^2 .

The lever D is held in engagement with the notch in the wheel B by a spring, d' , while the armature-lever E' is held out of contact with the electro-magnet by a spring, e ; and p is a
15 stop-pin that limits the movement of the armature in one direction, or away from the electro-magnet.

It will be seen that when the electro-magnet E attracts the armature-lever E' the outer
20 end, e^2 , of the latter will engage the free end of lever D and disengage its hooked end d^3 from the notch of the transmitter-wheel B, which, under the action of the train of clock mechanism C, will make one revolution, during
25 which the contact points or strips on the periphery of the wheel will successively pass under the contact-spring B and successively interrupt the main circuit, and transmit to the indicating or recording instrument F at
30 the main station a series of electric impulses, from the nature of which the location of the local station from which the signals are transmitted is made known, the line-current, as above stated, passing from the battery Y at
35 the central station through the recording-instrument and line-wire to spring b, the wheel B, and wire b^4 to earth. The arm D of lever D is formed in two sections, the outer section, d^3 , being articulated to the inner section, so as
40 to swing upward. This is necessary to allow the armature-lever E' to return into its normal position after having been attracted by the electro-magnet and actuated the lever D, as described.
45 The local circuit is normally interrupted by the connections with the points to be protected or guarded, these connections being so arranged that when tampered with the local circuit will be closed and the operations above
50 described result therefrom.

In order that an attempt at burglary or the breaking out of a fire may be made known on the premises themselves—to a watchman, for instance—I interpose a signaling-instrument, K, in a derived or secondary circuit, H', such 55 signaling-instrument being of any desired or preferred construction to give either a visible or an audible signal, or both. This secondary circuit is normally interrupted and is closed simultaneously with the closure of the local 60 circuit by the armature-lever E', which has an arm, e^3 , to which is secured a contact-spring, e^5 , that makes contact with a screw, e^4 , the current passing from local battery X to signaling devices K, thence to lever-spring e^5 , 65 contact-screw e^4 , back to battery, while the local-circuit currents pass from battery X to points h h h , &c., to electro-magnet and back to battery, as shown in Fig. 1.

I have deemed it unnecessary to illustrate 70 in detail the recording or indicating instrument at the central station, or the connection of the local circuit with the various points of a local station to be protected in case of fire or an attempt at burglary, for the reason that 75 the construction of such instrument and the connections are well known, and the latter vary according to the nature of the part to which they are applied, and for the further reason that they do not form a part of my invention. 80

Having now described my said invention and how the same is to be performed, what I claim, and desire to secure by Letters Patent, is—

85 The combination of the electro-magnet E, the circuit-breaker B, provided with an annular projection having a notch in its periphery, with the lever D, having the articulated or hinged arm-section d^3 , and the armature-lever E', said parts being arranged for operation substantially as and for the purpose specified.

In testimony whereof I affix my signature in presence of two witnesses.

SIGFRIED TAUSSIG.
